UNITED STATES PATENT OFFICE

165,130

COMBINED SIGNAL LAMP AND GUARD

Clark M. Bolser, Cedar Falls, Iowa, assignor to
The Bolser Corporation, Cedar Falls, Iowa, a
corporation of Iowa

Application April 28, 1951, Serial No. 15,011

Term of patent 14 years

(Cl. D72—1)

To all whom it may concern:

Be it known that I, Clark M. Bolser, a citizen of the United States, and a resident of Cedar Falls, county of Blackhawk, State of Iowa, have invented a new, original, and ornamental Design for a Combined Signal Lamp and Guard, of which the following is a specification, reference being had to the accompanying drawing, forming a part thereof, in which:

Figure 1 is a perspective view of a combined signal lamp and guard, showing my new design.

Figure 2 is a top plan view thereof.

Figure 3 is a front elevational view thereof; and

Figure 4 is a side elevational view thereof.

I claim:

The ornamental design for a combined signal lamp and guard, substantially as shown.

CLARK M. BOLSER.
